WILLIAM J. O'LEARY, OF MONTREAL, QUEBEC, CANADA, ASSIGNOR TO MARGUERITE V. O'LEARY, OF MONTREAL, QUEBEC, CANADA.

OSCILLATING MOTOR.

1,327,250.

Specification of Letters Patent. Patented Jan. 6, 1920.

Application filed February 28, 1918. Serial No. 219,627.

To all whom it may concern:

Be it known that I, WILLIAM J. O'LEARY, a subject of the King of England, residing at Montreal, Dominion of Canada, have 5 made a certain new and useful Invention in Oscillating Motors, of which the following is a specification.

This invention relates broadly to mechanical movements, and more particularly 10 to a motor for producing oscillatory movement.

The principal object of the present invention is a mechanism for producing oscillatory movements without the use of cams or 15 gears, and more especially by motive power applied directly to the part to be oscillated.

More particularly the object of the present invention comprises oscillatory motors for applying power from a continuously vibrating member to the member to be oscillated whereby the effective power is continuously applied to said member first in one direction and then in the opposite direction. 20

Still more specifically the present invention 25 comprises a mechanism of the character specified wherein the motive power is a vibration motor with the vibratory band bifurcated and having one part extending in one direction around the member to be oscillated, and the other part extending in the opposite direction around the member to be oscillated.

A still further and equally important object of the present invention comprises a 35 mechanism of the character previously specified and wherein the anchored ends of the vibratory band are operatively connected with a mechanism which alternately loosens and tensions the said band whereby while one part is tensioned, the other part is loosened.

A still further object of the present invention is a device of the character specified and wherein the tensioning on the band 45 renders it effective, while the loosening of the band renders the same ineffective, so that it will be noted that since the bands pass in different directions around the member to be oscillated, and since the bands are alternately rendered effective and ineffective, the said member will be alternately rotated in opposite directions. 50

More specifically the present invention comprises an energized vibrating fork having a pair of vibratory bands operatively

connected to the vibrating fork with one of said bands passing in one direction around a pulley to be driven, the other of said bands passing in the other direction around the pulley to be driven, and with the 60 ends of said bands secured to a tension controlling device whereby one of said bands is tightened around the pulley, while the other of said bands is loosened, this causing the tightened band to be effective to drive 65 the pulley, and the loosened band to be ineffective.

A more specific, though preferred form, of the present invention comprises a device of the character previously specified wherein the vibrating fork is energized through the medium of an electro-magnet, and while the electro-magnet may be adapted to be operated by any type of electrical current, the preferred form herein illustrated is 70 adapted for operation by an alternating current, the frequency of which is substantially coincident with the natural period of vibration of the vibrating fork. 75

Other and further objects of the present 80 invention will in part be obvious and will in part be pointed out hereinafter in the specification following by reference to the accompanying drawings wherein like parts are represented by like characters throughout 85 the several figures thereof.

Figure 1 is a plan view more especially illustrating the motor without reference to the details for tightening the band.

Fig. 2 is a detail view illustrating in perspective one type of mechanism for controlling the tension on the bands. 90

Fig. 3 is a plan detail view of the same tensioning device shown in Fig. 2.

Fig. 4 is an elevational view showing one 95 side of the vibrating fork broken away to more clearly illustrate the relation of the vibratory bands and tightening mechanism for the bands.

Oscillatory mechanism more particularly 100 as applied to washing machines, churning, and the like, heretofore in the art may be divided broadly into two classes, one class comprising mechanisms wherein an oscillatory motion of a fixed non-adjustable period is provided through the medium of a continuously 105 rotating member; this class includes pitmen, cranks, and cams. The second class comprises devices for producing oscillatory motion by permitting a rotation motion for 110

a predetermined period of time and then suddenly stopping and reversing the said rotating motion. This type includes belt shifting devices, or gear change devices usually under control of some separate periodic determining devices. These devices are usually susceptible of adjustment. The device comprising the present invention relates more particularly to the second class but is 10 widely different in operation from any known device in either class.

The present invention is characterized more particularly by the continued application of power to a vibrating member and the 15 alternate application of power from the vibrating member to the member to be oscillated and wherein the power is applied through a vibratory band.

One preferred embodiment of the present 20 invention comprises a tuned fork of elastic material, preferably steel, with a simple electro-magnet or solenoid having a soft iron core with the poles of the core between the arms of the fork, and wherein the tuning 25 of the fork substantially corresponds to a standard alternating current of say sixty (60) cycles per second. This arrangement provides a construction whereby application of suitable alternating electric current to 30 the electro-magnet causes continued vibration of the fork. A pair of connecting members, preferably of shellacked leather, are attached to each prong of the fork and joined together with vibratory bands secured 35 to these members at their junction. These vibratory bands are passed around a rotary member which may comprise a pulley, one band being on one side of the pulley and the other band being on the other side. 40 The free ends of these bands preferably carry light coiled springs which in turn are anchored to posts on an oscillating plate; the purpose of these springs is to maintain a suitable tension on the bands when the 45 springs are extended. The oscillating plate is adapted to be latched and held at its extremity of oscillation. A pair of springs, one on each side of said plate are secured to the plate and to a relatively large sized 50 control pulley. This pulley is provided with pins which may be inserted in holes provided in the pulley and which pins are constructed to contact with the latches, so that as the control pulley revolves one of these 55 pins strikes the latch and lifts the same permitting the tensioned spring to swing the latch to its other extreme limit of oscillation, at which point it is again secured by the other latch. This swinging of the plate re- 60 verses the tension on the vibratory bands and thus reverses the motion of the member being driven. The control pulley is driven by a band from a small pulley carried by the shaft which carries the member being 65 oscillated.

The fundamental principle of the motor comprising a part of this invention may be better understood by reference to Melde's experiment (*Watson's Physics*, 4th edition, page 402), wherein a tuning fork is provided 70 with a vibratory string tensioned by weights. When this experiment is being carried out the weights are substantially stationary except at the very beginning of the vibration of the fork. When the weights are stationary 75 the weighted end of the string is substantially stationary whereas the end secured to the fork has a linear movement equal to the vibration of the fork. Melde's experiment consists further in the adding 80 or subtracting weights to increase or decrease the tension on the string and observing the relationship between the weights and character of string vibration. By departing from Melde's experiment and bringing a 85 freely rotatable spool against the string the spool will revolve toward the fork, due to the tightening and loosening of the string by the fork vibration. Such is the basic principle of the motor herein disclosed. 90

Referring now more particularly to the drawings, the motor frame 1 carries a vibrating fork 2, the prongs of which are suitably weighted, as at 4, to synchronize the vibration of the fork with the alternations 95 of the circuit with which the motor is adapted to be energized. A solenoid or electric coil 5 is mounted between the forks with the pole pieces 6 and 7 of the core 8 extending between the fork so that when the solenoid 100 is energized by a suitable alternating current the magnetism acting through the pole pieces 6 and 7 vibrates the prongs of the fork 2. A pair of connector straps 9 and 10, which may comprise shellacked leather 105 straps or other suitable material, are riveted, as at 11 and 12, to the inner sides of the prongs of the fork 2, and have their free ends joined together by means of a rivet or other suitable connector 14, with a pair of vibratory bands 15 and 16 secured between the free ends of the straps 9 and 10. These vibratory bands extend upon opposite sides and encircle the pulley 17 which comprises the member to be oscillated, and have their 110 free ends 19 and 20, respectively, connected through coiled springs 21 and 22 to anchor posts 23 and 24 carried by the swinging plate 25. This swinging plate 25 is mounted to freely turn on a stub screw or post 26 115 and may be provided with an arm 27 which is adapted to latch into and be held by notched levers 28 and 29. These levers are pivoted on posts comprising stub screws 30 and have extensions 31 and 32 against which 120 the leaf springs 34 and 35 bear to maintain the extensions against the stop screws 36 and 37. The shaft 38 of the drive pulley 17 carries a small band pulley 39 which is connected, by a driving band or belt 40, with a 125 130

relatively large control wheel 41. This control wheel rotates idly upon a post carrying the stub screw 26 and is provided with rows of openings 42 and 44. These openings comprise receptacles to receive and support control posts 45. These control posts 45 are adapted to engage cams 46 and 47 on the notched levers 28 and 29 and disengage these notched levers from the arm 27 of the swinging plate 25. Coiled springs 48 and 49 are anchored at one end to the control wheel 41 and at the other end to the arm 27 on the swinging plate 25. The sides of this plate, as at 50 and 51, are of sufficient enlargement and contour to support the coiled springs 48 and 49 when the springs are drawn around the edge of the plate.

The operation of the particular embodiment of the invention herein illustrated comprises a continued vibration of the fork 2 by the energizing of the solenoid 5 with proper alternating electric current whereby the vibration from the fork is transmitted through the connector straps 9 and 10 to the vibratory bands 15 and 16. Assuming one of these bands (as illustrated in Fig. 3) to be under tension the drive pulley 17 will rotate around the end of that particular band that is attached to the straps 9 and 10. This rotation turns the small pulley 39 which drives the control wheel 41 whereby the control wheel is slowly rotated in the same direction as the driving pulley 17, since the arm 27 of the oscillatory plate 25 is held by the notched lever 28. The continued rotation of the control wheel extends the coiled spring 49. This extension continues with the rotation of the control wheel until the control post 45 engages the cam 46 which moves the notched lever 28 outwardly and releases the arm 27. The extended coiled spring 49 quickly swings the arm 27 into engagement with the other notched lever 29 where the arm is locked. When this has happened, the vibrating band 9 is drawn taut and the band 10 is relaxed. Because of the law of operation of this type of vibrating motor, the pulley 17 immediately reverses its rotative action and therefore reverses the direction of rotation of the control wheel 41 which at once begins to extend the coiled spring 48 and the action of the parts is repeated. By increasing the angle between the posts 45, as measured at the axis of the control wheel, the number of revolutions of the drive pulley 17 in the oscillatory period is increased, whereas by diminishing this said angle the period of revolutions is decreased. The said angle is decreased or increased by changing the control posts 45 in the row of control openings 42 and 44 in the control wheel.

While there are many novel features to this invention it is believed that the essence of the invention resides in the two vibrating

bands coöperating with each side of the drive pulley and any suitable mechanism which renders first one band and then another effective to rotate the driven member.

Realizing that the present invention may be embodied in structures other than those specifically disclosed herewith it is my desire that this disclosure herewith be understood as illustrative and not in the limiting sense.

Having thus described my invention what I claim is:

1. A device of the character described, comprising, in combination, a vibrating member, connector means secured to said vibrating member, a pulley to be oscillated, a pair of bands secured to said connector means and extending in opposite directions on each side of said pulley, anchoring means to which the ends of said bands are secured, and devices for alternately tensioning said bands to cause alternate rotative movement of said pulley.

2. A device of the character described, comprising in combination, a rotating member adapted to be oscillated, a pair of bands, one extending in one direction around said member, the other extending in the opposite direction around said member, means to produce vibration of said bands, and devices to alternately tension said bands around said member whereby the tensioned band is effective to cause rotation of said member and whereby the alternating of the tension of the band causes said member to be driven first in one rotative direction and then in the other rotative direction.

3. A device of the character described, comprising in combination, a member to be oscillated, a pair of vibrating bands one extending on each side of said member, means to vibrate said bands, a swinging anchoring member, means operatively connecting the ends of said bands to said swinging member, and devices for swinging the swinging member to tension first one of said bands and then the other.

4. In a device of the character described, in combination, a member to be oscillated, a vibrating fork, a connector secured to said vibrating fork, a pair of bands anchored to said connector and extending on each side of said member to be oscillated, yielding means secured to the ends of said bands, and a swinging member to which said yielding means is anchored whereby when said swinging means is operated the yielding means may be alternately tensioned to alternately bring the bands into effective relation with the member to be oscillated whereby the said member is rotated first in one direction and then in the other direction.

5. In a device of the character described, in combination, a member to be oscillated, a vibrating fork, connector means secured to

each prong of said fork, vibrating bands anchored to said connector means and extending on each side of a member to be oscillated, and devices for alternately rendering said bands effective to drive said member whereby said member is driven in one direction and then in the other direction.

6. A device of the character described, comprising in combination, a vibrating member, connector means secured to said vibrating member, a pulley to be oscillated, a pair of bands secured to said connector means and extending in opposite directions on each side of said pulley, a swinging plate, spring means to urge said plate to swing, holding means to prevent such swinging, and devices for releasing said holding means to enable said plate to swing under influence of said spring means.

2) 7. In a device of the character described, in combination, a vibrating member, a pair of bands operatively connected with said vibrating member, a pulley adapted to be oscillated, one of said bands being effective 25 to drive said pulley in one direction and the other of said bands being effective to drive said pulley in the other direction, means for determining which of said bands shall be operative, said last mentioned means comprising an anchoring member to which the free ends of said bands are connected, a control device, and adjustable means for adjusting the effective operation of said control device.

8. In a device of the character described, 35 in combination, a vibrating member, connector means secured to said vibrating member, a pulley to be oscillated, a pair of bands secured to said connector means, and devices for alternately tensioning said bands, said 40 devices comprising a control wheel driven from said oscillating pulley and constructed to operate mechanism for tensioning first one of said bands and then the other.

9. A device of the character described, 45 comprising in combination, a vibrating fork, driving bands connected with said vibrating fork, a member to be oscillated and around which said bands are adapted to pass, a swinging plate to which the free ends of said bands are connected, means to latch said plate in one direction, means tending to move said swinging plate in the opposite direction, and a control wheel for releasing said latch when said pulley has made 50 a predetermined number of revolutions.

10. A device of the character described,

in combination, a member to be oscillated, driving mechanism for oscillating said member, a control wheel driven from the member to be oscillated, a swinging plate, springs 60 connected to said swinging plate and to said control wheel, latches adapted to hold said swinging plate against movement, latch operating pins mounted on said control wheel and adapted to operate said latches 65 to release said swinging plate to permit the springs to operate said plate, and connections between said swinging plate and said driving mechanism whereby said oscillatory member is driven first in one direction and then in the other direction. 70

11. A device of the character described, in combination, a vibrating fork, a member to be oscillated, driving bands operatively connected with said fork and with said member to be oscillated, means for rendering first one of said bands and then the other operative to drive the member to be oscillated, said means comprising a swinging plate to which the free ends of the driving 80 bands are anchored, control mechanism for determining the movement of said plate, said control mechanism including a rotating control wheel, latches for holding said swinging plate, and pins carried by said 85 wheel for unlatching the particular latch which is holding the swinging plate after the member to be oscillated has completed a predetermined number of revolutions.

12. In a device of the character described, 90 in combination, a vibrating fork, a device adapted to be oscillated, driving means between said fork and said device, and mechanism for rendering said driving means effective to rotate said device in one direction 95 for a predetermined number of revolutions and then rendering said driving mechanism effective to rotate said device a predetermined number of revolutions in the other direction.

13. The method of producing oscillatory motion, which consists in vibrating a pair of bands; extending one band in one direction around the member to be oscillated; extending the other band in the opposite direction around the member to be oscillated; then alternately tensioning said bands to cause the motion in said bands to drive said member first in one direction and then in the other direction. 100 105

WILLIAM J. O'LEARY.
